UNITED STATES PATENT OFFICE.

WILLIAM M. TINNISWOOD, OF SANTA MARIA, CALIFORNIA.

BREATHER FOR ENGINES.

Application filed April 27, 1923. Serial No. 635,135.

To all whom it may concern:

Be it known that I, WILLIAM M. TINNISWOOD, a subject of the King of Great Britain, and resident of Santa Maria, in the 5 county of Santa Barbara and State of California, have invented certain new and useful Improvements in Breathers for Engines, of which the following is a specification.

This invention relates to breathers for internal combustion engines.

Briefly stated an important object of this invention is to provide an auxiliary air supply means for the crank case of an internal combustion engine and more particularly to 15 the engine of the Ford automobile so that the internal pressure in the engine crank case is reduced to a minimum.

A further object of this invention is to provide a breather which may be efficiently 20 installed on engines either during manufacture or at any time thereafter without elaborately altering the construction of the same and without the exercise of unusual skill.

25 A further object of the invention is to provide a breather member for internal combustion engines which is of highly simplified construction, durable in use and cheap to manufacture.

30 Other objects and advantages will be apparent during the course of the following description.

In the accompanying drawing, forming a part of this application and in which like 35 numerals are employed to designate like parts,

Figure 1 is a side elevation of the improved breather applied.

Figure 2 is a longitudinal sectional view 40 through the same, the sections of the breather being separated.

Figure 3 is a group perspective of the improved breather.

In the drawing wherein for the purpose 45 of illustration is shown a preferred embodiment of the invention, the numeral 5 generally designates an internal combustion engine having a crank case 6 upon which the cylinders 7 are mounted in the usual manner.

50 The invention forming the subject matter of this application is especially adapted for use on the engine used in the Ford automobile and it will be seen that a transmission 8 is arranged within the transmission housing 9 arranged at the rear end of the

crank case. The transmission housing 9 is as illustrated in Figure 1 provided with a detachable cover section 10 having its upper side provided with an elongated opening 11 by means of which access is ordinarily had 60 to the engine transmission.

The cover plate ordinarily secured over the opening 11 is imperforate and consequently the movement of air through the transmission and into the crank case is prevented. However, in carrying out this invention the cover plate for the opening 11 is in the nature of three sections designated by the numerals 14, 15 and 16, the plate 14 being the outer section, the plate 15 being 65 the intermediate section and the plate 16 being the lower section. The several plates are securely and detachably joined by means of screw bolts 18 which are passed through aligned openings 120 in the plates and 70 threaded into openings in the cover or upper half 10 of the transmission housing.

The air may circulate through a transverse opening 20 in the lower portion of the bottom plate 16 and the air which passes 80 through the opening 20 encounters a plurality of baffle angle bars 24 secured in any suitable manner to the underside of the intermediate plate 15. If air is passing outwardly through the opening 20 it will encounter the baffles 24 and any solid particles of oil suspended in the air will be collected 85 by the baffles 24.

The oil thus collected by the baffles 24 will drip into the recessed bottom 26 of the 90 lower plate 16 and will then return to the transmission housing by way of the transverse opening 20.

Figure 3 illustrates that the upper portion of the intermediate plate 15 is formed 95 with a transverse opening 28 for the passage of air after the oil has been removed therefrom by the baffles 24. The air which passes through the transverse opening 28 will contact with the raised portion 30 of the upper 100 or top plate 14 and will then pass out through a rather large opening 29 in the lower portion of the top plate.

Attention is directed to the fact that the oil is positively prevented from escaping 105 from the transmission housing by way of the invention forming the subject matter of this application as the intermediate baffle member 15 is provided with reliable means by which the oil suspended in the air is re- 110

moved and returned to the transmission housing. Therefore the exterior of the transmission housing is maintained more or less free from oil in the vicinity of the auxiliary breather.

It will be seen that the air may circulate through the breather and thereby relieve the internal pressure in the crank case. Also the invention forming the subject matter of 10 this application can be applied to an engine either during the course of manufacture or at any time thereafter without altering the engine in any way and without the exercise of unusual skill, all of which contribute to 15 the desirability and salability of the attachment.

It is to be understood that the form of the invention herewith shown and described is to be taken as a preferred example of the 20 same and that such minor changes in arrangement and construction of parts may be made as will remain within the spirit and scope of the invention as claimed.

Having thus described the invention, 25 what is claimed is:—

1. An auxiliary breather for internal combustion engines comprising a cover plate adapted to be applied to the transmission housing provided with a chamber therein, 30 said cover being provided with openings forming respectively inlet and outlet ports, a plate extending longitudinally of the chamber and provided with a plurality of diagonally extending baffles by means of

which the oil suspended in the air passing 35 through the breather is removed.

2. An auxiliary breather for internal combustion engines comprising a top, intermediate and bottom plate, means whereby the plates may be secured together and across 40 the opening of a transmission housing, the intermediate plate being provided on its under side with a plurality of diagonally extending angle bars constituting baffles by means of which the oil contained in the air 45 is removed, the lower plate being provided with a recessed bottom for receiving said baffles and a transverse opening at its lower end for the passage of air and oil, the top plate being provided with a raised portion 50 defining a shallow chamber, the intermediate plate being provided with a transverse opening directly beneath the shallow chamber and communicating therewith.

3. In an article of manufacture, a combined cover plate and breather for internal combustion engines comprising, top, intermediate and lower plates, the intermediate plate being provided with diagonally extending angle bars constituting baffles for 55 collecting oil, the bottom plate being provided with a transverse air passage and a recessed bottom directly beneath said baffles, the intermediate plate being also provided with a transverse opening for the passage of 60 air and the top plate being provided with an opening communicating therewith.

WILLIAM M. TINNISWOOD.
